UNITED STATES PATENT OFFICE.

CHARLES H. SHAW, OF NEW YORK, N. Y.

PANORAMIC CAMERA.

SPECIFICATION forming part of Letters Patent No. 624,553, dated May 9, 1899.

Application filed December 16, 1898. Serial No. 699,431. (No model.)

To all whom it may concern:

Be it known that I, CHARLES H. SHAW, a citizen of the United States, residing in the borough of Brooklyn, city and State of New York, have invented certain new and useful Improvements in Cameras, of which the following is a specification.

My invention relates to cameras, and more particularly to that class of cameras known to as "panoramic" cameras.

I will describe a camera embodying my invention and then point out the novel features in the claims.

In the accompanying drawings, Figure 1 is a horizontal sectional view of a camera embodying my invention. Fig. 2 is a vertical sectional view of the casing and showing a rear elevation of the camera parts. Fig. 3 is a vertical sectional view. Fig. 4 is a detail cross-sectional view of a lens-cylinder and a light-shaft. Fig. 5 is a perspective view of the camera.

Similar letters of reference refer to corresponding parts in all of the figures.

A represents a suitable casing for containing the several parts of the camera. One of its walls—as, for instance, the wall A'—is detachable from the remainder of the casing, and it is to this wall that I connect two plates, between which plates several parts of the camera mechanism are located and held. This arrangement permits of the working parts of the camera being removed from the casing for examination and the substituting of one film for another.

B B' represent the two plates that are connected to the wall A' and which extend outwardly therefrom. These plates are detachably connected to protruding parts a of the wall A'. The parts a may be integral with the wall A' or separate therefrom, in which case they are held by screws a'. Between the two plates B B' and at the sides thereof I locate walls b. These walls may be supported by standards b', to which they are secured, and the standards may be held at their ends between the two plates. These standards also serve to support the plates B B' and to space them apart. The purpose of these walls b is to exclude light from that part of the film not within the path of movement of a light-shaft that is employed in the camera.

C represents a cylinder placed vertically in an opening provided in the wall A'. It is preferably arranged to have a portion projecting beyond the outer surface of the wall A'. It is arranged to oscillate in the opening on journals that are provided in the ends of the cylinder. These journals may conveniently consist of circular plates c, that fit in the ends of the cylinder C. These plates may be carried by the plates B and B', being secured thereto by any desired means—as, for example, by solder. The cylinder is provided with an opening c' in that portion of its wall projecting beyond the wall A, and diametrically opposite this opening is a second opening, into which one end of the light-shaft c² is secured. The light-shaft is preferably rectangular in cross-section and is adapted to move with the cylinder, and it is of such a length as to have its free end move in a plane that is parallel with and adjacent the film or other sensitized surface used in the camera.

c³ represents a lens that is carried by a suitable holder c⁴. The holder c⁴ is inserted in an opening provided in a wood or other block c⁵, that is held within the cylinder C. The lens is placed in the line of the openings in the cylinder C, so as to project the light-rays through the light-shaft onto the sensitized surface. When the cylinder C, carrying the lens, is oscillated with the lens exposed, the light-rays from the different parts of the view being photographed will be projected by the lens through the light-shaft onto successive portions of the film or plate in the camera as the light-shaft is moved in front thereof. The cylinder may be oscillated in one direction by means of a coiled spring c⁶, that is preferably located within the cylinder. One end of the spring is secured to a stationary part—as, for example, to a pin c⁷, carried by one of the plates c—while the other end of the spring may be secured to the cylinder. The cylinder and light-shaft may be moved in the other and opposite direction for the purpose of "setting" the lens and light-shaft by hand. When the cylinder is moved in this direction, the spring is placed under tension to move the cylinder and light-shaft in the first-mentioned direction—that is, in the direction to expose the film. It is obvious that the speed of the

lens-cylinder and light-shaft may be regulated by changing the tension of the spring. The joint made by the wall of the cylinder and the walls of the opening in the part A', 5 in which the cylinder is placed, may be made light-proof in any convenient manner, as by felt ^{c¹⁰} or metal, which would conform to the wall of the cylinder. Any desired means may be employed for holding the light-shaft and cylinder in "set" position and for releasing them from set position. I have shown in the drawings, the following arrangement of parts 10 for doing this. A lever D is pivoted to the upper plate B, so as to have one of its ends d in the path of movement of the light-shaft. As the light-shaft is moved to set position this end d will be made to engage with the light-shaft to hold it against the action of the spring c⁶. A flat spring d' is preferably provided for holding the end d in the path of 15 movement of the light-shaft. The other end d² of the lever is so arranged as to be engaged by a button d³, carried by the casing A, which when depressed to engage the end d² causes the end d to move out of engagement 20 with the light-shaft. A shutter c⁸ may be provided in the cylinder to cover the lens when desired, a knob or projection c⁹ being provided for moving it over the lens after the 25 film has been exposed and the cylinder and light-shaft are to be reset. This knob or projection may also be used to move the cylinder and light-shaft to set position.

E E' represent shutters which are provided 30 for the end of the light-shaft. One of the shutters is provided for closing the end of the light-shaft when the camera is in set position, while the other shutter is for closing the end of the light-shaft after it has been 35 released from set position and it has moved in front of the film to expose it. With this arrangement of the shutters for the end of the light-shaft all light-rays from the lens are excluded from the camera while the light-shaft is at rest. These shutters are operated 40 automatically and preferably by the light-shaft coming into engagement with them. Each shutter may conveniently consist of an L-shaped piece of metal that is provided with 45 a pivot e at each end, which pivots have a bearing in the plates B and B'. A spring e² is provided for each shutter for the purpose of holding it in such position as to be operated by the light-shaft. These springs are 50 preferably flat ones, and they are secured at one of their ends to the walls b. The operation of these shutters is as follows: When the light-shaft and cylinder are moved to set 55 position, the light-shaft engages with one arm e³ of the shutter, against which the spring e² bears, and moves it against the action of the spring so as to bring the other arm e⁴ of the shutter over the open end of the light-shaft to completely close it. When the light-shaft 60 is released to expose the film, the end of the light-shaft moves away from the arm e⁴ to throw the light-rays onto the film. As it

moves in front of the film it comes into engagement with the arm e³ of the shutter E' and moves this arm to cause the arm e⁴ of this shutter to completely close the end of the light-shaft, and thus prevent any more light-rays entering the interior of the camera. The shutter c⁸ is then moved over the lens and the cylinder and light-shaft reset for another exposure. After the cylinder and light-shaft have been reset the shutter c⁸ is moved from in front of the lens, thus having the camera ready for another exposure. It will be seen, therefore, that the purpose of the 80 shutter c⁸ is merely to cover the lens while the camera is being reset and also to protect the lens from dust, &c., when not in use.

A film is preferably used in the camera, and provision is made for inserting in the 85 camera the spool, on which the film is generally wound, and unwinding the film from the spool as it is needed onto a second spool. F represents the spool carrying the film f, and F' the spool onto which the film is wound. The 90 spool F' is provided with the usual ratchet and the pawl engaging therewith, and this spool is turned by the usual key f², carried by the casing A.

The rollers F and F' are removably held in 95 spring-pieces f³, that may be secured to the plates B and B' on the outside thereof by rivets, which rivets are located at the middle of the pieces. These pieces are near the wall A' of the casing, so that the spools will be in 100 the position shown in the drawings. The film from the spool F is passed over a roller f⁶, journaled in the plates B B', and preferably against curved flanges f⁴, that are carried by the said plates, and over a roller f⁵ to 105 the spool F'. Guide-rods f⁷ may also be provided to prevent the film moving away from the flanges while being transferred from one spool to the other. The usual opening A³ and its colored covering A⁴ are provided in the 110 casing A in order that the position of an unexposed part of the film may be gaged through the usual marks or signs provided on the back- 115 ing of the film.

What I claim as my invention is—

1. In a camera, the combination of a lens, means for moving said lens in an arc from one position to another, a light-shaft through which the lens projects light-rays onto a sensitized surface, said light-shaft adapted to be 120 moved with said lens; an L-shaped shutter supported lengthwise and independent of the light-shaft and lens for closing the end of said light-shaft in one position, and a second L-shaped shutter supported lengthwise and also 125 independent of the light-shaft and lens for closing the end of the light-shaft in its other position.

2. In a camera, the combination of a lens, means for moving said lens from one position 130 to another, a light-shaft moving with said lens through which the lens projects light-rays onto a sensitized surface, and means independent of the light-shaft and lens that are

operated by the light-shaft engaging therewith for closing the end of said light-shaft at the limit of its movement in each position.

3. In a camera, the combination of a lens, means for moving said lens from one position to another, a light-shaft moving with said lens, through which light-rays are projected onto a sensitized surface, and a shutter independent of the light-shaft and lens for closing the end of said light-shaft in each of its positions, said shutter being L-shaped, and arranged to have the light-shaft engage with one arm thereof to bring the other arm in position to close the end of the light-shaft substantially as described.

4. In a camera, the combination of a suitable casing, a cylinder provided in a wall of said casing and mounted therein so as to be vertical, diametrically-opposed openings in the wall of said cylinder, a lens located within the cylinder and in the line of said openings, and a light-shaft connected with said cylinder through which the light-rays are projected by the lens onto a sensitized surface, substantially as described.

5. In a camera, the combination of a suitable casing, a cylinder provided in a wall of said casing and mounted therein so as to be vertical, means for excluding light between the wall of said cylinder and the wall in which it is mounted, diametrically-opposed openings provided in the wall of said cylinder, a lens within said cylinder, and in the line of said openings, and a light-shaft carried by said cylinder through which light-rays are projected onto a sensitized surface, substantially as described.

6. In a camera, the combination of a casing, a cylinder provided in the wall of said casing and mounted therein so as to be vertical and to be oscillated, means for oscillating said cylinder, diametrically-opposed openings provided in the wall of said cylinder, a lens within the cylinder located in the line of said openings, and a light-shaft carried by said cylinder through which light-rays are projected onto a sensitized surface, substantially as described.

7. In a camera, the combination of a casing, a cylinder provided in a wall of said casing and mounted therein so as to be vertical and to be oscillated, a spring for oscillating said cylinder in one direction, diametrically-opposed openings provided in the wall of said cylinder, a lens located within the cylinder and in the line of said openings, and a light-shaft connected with said cylinder through which light-rays are projected onto a sensitized surface, substantially as described.

8. In a camera, the combination of a casing, a cylinder provided in the wall of said casing and mounted therein so as to be vertical and to be oscillated from one position to another, diametrically-opposed openings in the wall of said cylinder, a lens located within the cylinder and in the line of the openings, a shut-

ter for said lens, a light-shaft connected with said cylinder so as to move with it through which light-rays are projected onto a sensitized surface, and a shutter independent of the light-shaft and cylinder for closing the end of said light-shaft in each of its positions, substantially as described.

9. In a camera, the combination of a casing, having one wall detachable therefrom, which wall is provided with an opening, plates secured to said wall and extending outwardly therefrom, a cylinder arranged vertically in the opening in said wall and having diametrically-opposed openings in its wall, means for journaling said cylinder at its ends so that it can be oscillated from one position to another, means for oscillating it from one position to another, a device for holding the cylinder against the action of said means and releasing it, a lens located within said cylinder and in the lines of the openings in the wall thereof, a shutter for said lens, a light-shaft connected to and moving with said cylinder from one position to another through which light-rays are projected onto a sensitized surface, and shutters mounted between said plates, independent of the light-shaft for closing the end of the light-shaft in each of its positions, said shutters being adapted to be operated by the light-shaft engaging therewith, substantially as described.

10. In a camera, the combination of a casing having one wall detachable therefrom, which wall is provided with an opening, plates secured to said wall and extending outwardly therefrom, a cylinder having diametrically opposite openings in its wall arranged vertically in said opening and journaled at its ends in said plates so as to be oscillated from one position to another, a lens within said cylinder and in line with said openings, side walls between said plates, a light-shaft secured to said cylinder and moving with it through which light-rays are projected onto a sensitized surface, and means for closing the ends of said light-shaft in each of its positions, substantially as described.

11. In a camera, the combination of a casing having one wall detachable therefrom, said wall being provided with an opening, plates secured to said wall and extending outwardly therefrom, a cylinder having diametrically opposite openings in its wall arranged vertically in said opening, and journaled at its ends in said plate so as to be oscillated from one position to another, a lens located within said cylinder and in line with the openings in the wall thereof, a light-shaft secured to said cylinder and moving with it, means independent of the light-shaft for closing the end thereof in each of its positions, side walls supported between said plates between which the light-shaft moves, a spool carrying a sensitized surface which is adapted to be transferred to another spool, and spring-plates, secured to the outside of the plates secured to the

detachable wall, between which the spools are removably held, substantially as described.

12. In a camera, the combination of a casing having one wall detachable therefrom, said 5 wall being provided with an opening, plates secured to said wall and extending outwardly therefrom, a cylinder having diametrically opposite openings in its wall arranged vertically within the opening in said detachable wall and adapted to be oscillated from one limited position to another limited position, means for oscillating said cylinder, a lens located within said cylinder and in line with the opposite openings, a shutter for said 15 lens, a light-shaft secured to and moving with said cylinder through which light-rays are projected onto a sensitized surface, and shutters mounted between said plates and arranged to close the end of the light-shaft in 20 each of its positions, substantially as described.

13. In a camera, the combination of a casing, having one wall detachable therefrom, which wall is provided with an opening, a cylinder 25 arranged vertically at the openings in said wall, and having diametrically-opposed openings in its wall, means for journaling said cylinder at its ends so that it can be oscillated from one position to another, a device for 30 holding the cylinder against the action of said means and releasing it, and a lens located within said cylinder and in the lines of the openings at the wall thereof, substantially as described.

14. In a camera, the combination of a casing, having one wall detachable therefrom, which wall is provided with an opening, a cylinder arranged vertically within said opening and provided with a lens, means for oscillating 35 said cylinder from one position to another, a light-shaft moving with said cylinder, and a shutter adapted to be operated by the light-shaft to close its end, substantially as described.

15. In a camera, the combination of a casing, having one wall detachable therefrom, which wall is provided with an opening, a cylinder arranged vertically within said opening, and

provided with a lens, means for oscillating said cylinder from one position to another, a 5c light-shaft moving with said cylinder, a shutter adapted to be operated by the light-shaft to close its end, and a spring for holding said shutter in position to be operated by the light-shaft, substantially as described. 55

16. In a camera, the combination of a casing, having one wall detachable therefrom, which wall is provided with an opening, a cylinder arranged within said opening and provided with a lens, means for oscillating said cylinder from one position to another, a light-shaft moving with said cylinder, and an L-shaped shutter supported lengthwise and adapted to be operated by the light-shaft to close its end, substantially as described. 60

17. In a camera, the combination of a casing having an opening in one of its walls, a cylinder arranged vertically in said opening, and having opposite openings in its wall, means for oscillating said cylinder in its vertical position, and a lens located in the line of said openings. 70

18. In a camera, the combination of a casing having an opening in one of its walls, a cylinder arranged vertically in said opening, and having opposite openings in its wall, means for oscillating said cylinder in its vertical position, a lens located in the line of said openings, and a shutter for said lens. 75

19. In a camera, the combination of a casing having an opening in one of its walls, a cylinder arranged vertically in said opening and having opposite openings in its wall, means for oscillating said cylinder in its vertical position, a light-shaft connected to and moving 80 with said cylinder, and a lens located in the line of the openings in the walls of the cylinder. 85

In testimony whereof I have signed my name to this specification in the presence of 90 two subscribing witnesses.
